(57) CLAIM

The ornamental design for an attached bed sheet set, as shown and described.

DESCRIPTION

FIG. 1 is a top perspective view of an attached bed sheet set, showing my new design;

FIG. 2 is a right side perspective view showing the design in use on a bed;

FIG. 3 is a left side perspective view showing the design in use on a bed; and,

FIG. 4 is a bottom perspective view.

The broken lines are for environmental purposes only and form no part of the claimed design.
